TYPE BAR MECHANISM FOR TYPEWRITERS

Alfredo Tombolini, Milan, Italy

Continuation of application Serial No. 30,387, July 8, 1935. This application August 2, 1939, Serial No. 288,056

1 Claim. (Cl. 197—22)

This invention relates to an improved type bar mechanism for typewriters and has for its object the provision of a mechanism of this character by the use of which the whole type bar set, together with the supporting segment and part of the intermediary levers may be downwardly shifted by depression of the capital letter key, thus eliminating the necessity for raising of the carriage for writing the capital letters.

To permit downward shifting of the whole set of type bars together with their supporting segment and part of their actuating levers, a new kinematic mechanism is necessary. This mechanism not only must allow the vertical shifting, but must also permit the actuation of the type bars by means of the key bars through intermediary levers, in both the normal and lowered position of the set.

There are known mechanisms for the purpose of vertically shifting the type bar set for writing capital letters. All of these known mechanisms, however, involve more or less considerable inconveniences, because they are too complicated, or so different from the existing normal mechanisms as to require a considerable transformation of the typewriter itself, or else because they require special type bars and do not allow for the use of normal type bars of the kind now employed by the most important manufacturers all over the world. Their use is further disadvantageous in that they do not allow exchange of the type bars individually, because they require a second semicircular segment underlying the supporting segment of the type bars, and because they present other constructional or functional defects.

The mechanism of this invention eliminates all the aforesaid inconveniences and at the same time assures equally good function in both the normal and lowered position of the type bar set. Furthermore, the leverage of the kinematic system is most favourable, all elements having pulling rather than pushing action.

In the accompanying drawing:

Figure 1 shows a type bar connected to the corresponding key bar with the intermediary levers; the broken lines show the lowered position of the elements which become lowered by depression of the capital letter key;

Figure 2 corresponds to Fig. 1, but the broken lines show the striking position of the key bar; and

Figure 3 is a perspective view which shows one half of the mechanism formed according to the invention.

Each key bar 1 is adapted to swing about a pivot 2 fixed to the frame of the typewriter, and carries a pin 3 to which one arm of a cranked lever 4 is connected. Each of the cranked levers 5 is adapted to swing at 5 about a straight pivot fixed to the frame of the machine and its other arm is connected to a strip 6 the opposite end of which is hinged to a shaped lever 7. Lever 7 is adapted to swing at 8 about a straight bridge 14 common to all of the levers 7 and being adapted to be vertically lowered by depression of capital letter keys, connected at the lateral ends thereof. The upper end of lever 7 carries a pin 9 by means of which said lever 7 engages a slot 10 of the type bar 11; the type bar 11 is adapted to swing at 12 about the segment pivot common to all type bars.

As will be clearly seen in Figure 3, the vertical arms of cranked levers 4 are all of the same length, while the horizontal arms of said levers become progressively longer from the center of the set toward the sides. Consequently the distance between points 5 and 3 progressively increases from the center towards the sides. This is necessary to compensate for the different leverage between elements 6 and 7, as the actuating levers 7 become also progressively longer from the center of the set towards the sides to follow the semicircular supporting segment of the type bars. Besides the progressive increase in the length of horizontal arms of levers 4 towards the sides, said horizontal arms have further different lengths in accordance with the key bars to which they are connected, because there are four groups 35 of key bars having different lengths. The strips 6 all have the same shape and length, are all on the same level and are individually detachably hinged to levers 7.

When a key 1 is depressed, the lever 4 is actuated and by means of strip 6 actuates the lever 7 and causes it to swing in forward direction about the pivot 8; the type bar 11 is thus swung about its pivot 12 and strikes the rubber roller of the carriage, as shown with dotted lines in Fig. 2.

As shown in Fig. 1 a portion of the mechanism may be lowered, namely the whole set of type bars 11 together with their supporting pivot 12, actuating levers 7, strips 6 and bridge 8, 14. For this purpose the type bar segment is appropriately guided in the frame of the machine and the usual capital letters are connected to the ends of bridge 14 so as to lower it when they become depressed. The normal position is restored by means of one or two internal springs.

In the mechanism described above, all parts work edgewise with pulling action. The consequence is that the keyboard is extraordinarily rigid (not springy).

A further feature of this mechanism lies in the simplicity of manufacture. For instance the angle-levers 4 and strips 6 may be manufactured all alike in shape and dimensions; the former may be easily shortened afterwards to give them the required lengths.

This application is a continuation of application Serial Number 30,387, filed July 8, 1935.

What I claim is:

In a typewriting machine, a frame, key bars pivoted on a common axis in said frame and having keys arranged thereon in different rows, a type bar supporting segment mounted for downward case shifting movement on said frame, type bars pivoted on said segment, a straight bridge connected to said segment for downward 20

shifting movement therewith, vertical actuating levers mounted on said bridge and having different lengths so as to follow the supporting segment of the type bars, said actuating levers being operatively connected to said type bars, uniform horizontal tension strips arranged on the same level and connected at one end to said actuating levers, a fixed straight pivot in said frame, and bell crank levers adapted to swing about said fixed straight pivot and having vertical arms connected to said key bars at different distances from said fixed straight pivot according to the different key rows and according to the different leverage of said actuating levers, said straight bridge and actuating levers being arranged behind the bell crank levers, and the key bars being downwardly offset to accommodate said straight bridge and fixed straight pivot and to allow downward shifting of said straight bridge.

ALFREDO TOMBOLINI.
